UNITED STATES PATENT OFFICE.

JOHN H. LAMPE, OF POCOHONTAS, IOWA.

DESIGN FOR A HARNESS-RACK.

45,639.

Specification for Design.

Patented Apr. 21, 1914.

Application filed October 7, 1913. Serial No. 793,955. Term of patent 7 years.

To all whom it may concern:

Be it known that I, JOHN H. LAMPE, a citizen of the United States, residing at Pocahontas, in the county of Pocahontas, State of Iowa, have invented a new, original, and ornamental Design for a Harness-Rack, of which the following is a specification, reference being had to the accompanying drawing, forming part thereof.

The figure is a view in perspective of the harness rack.

I claim:

The ornamental design for a harness rack, as shown.

JOHN H. LAMPE.

Witnesses:

J. F. RYAN,

F. H. BOOGE.
